TELEPHONE STERILIZER

Paul M. Brand, Fort Lauderdale, Fla., assignor to Dryster Corporation, Boca Raton, Fla., a corporation of Florida

Filed June 14, 1965, Ser. No. 85,707

Term of patent 14 years

(Cl. D83—1)

Fig.1

Fig.5

Fig.6

FIG. 1 is a perspective view of my telephone sterilizer;
FIG. 2 is a plan view thereof;
FIGS. 3 and 4 are side elevational views of opposite sides of the sterilizer; and

FIGS. 5 and 6 are views of the opposite ends of my sterilizer.

The broken lines are for illustrative purposes only.

I claim:

The ornamental design for a telephone sterilizer, substantially as shown and described.
